UNITED STATES PATENT OFFICE.

ARTHUR T. KUEHNER, OF ELKRIDGE, MARYLAND.

LOCOMOTIVE DRIVING BOX.

Application filed November 20, 1919. Serial No. 339,347.

To all whom it may concern:

Be it known that I, ARTHUR T. KUEHNER, a citizen of the United States, residing at Elkridge, in the county of Howard and State 5 of Maryland, have invented certain new and useful Improvements in Locomotive Driving Boxes, of which the following is a specification.

This invention relates to an improved 10 driving box for locomotives and has as one of its principal objects to provide a construction wherein the box may, without removing the locomotive drive wheels, be readily displaced.

15 The invention has as a further object to provide a box employing a detachable face plate, wherein the face plate may be readily released to be lifted out vertically and wherein the box body may then be shifted inwardly and removed.

20 A further object of the invention is to provide a construction wherein the face plate will be connected at its upper end to the upper end of the box body by fastening 25 devices while at its lower end the box body will itself be provided with means for locking the lower end of the face plate thereto to thus eliminate the use of fastening devices at the lower end of the box body.

30 And the invention has as a still further object to provide a construction wherein the face plate fastening devices employed will be retractible upon the box body for releasing the face plate but wherein said fastening 35 devices will, nevertheless, be held against accidental displacement from the box body.

Other and incidental objects will appear hereinafter.

In the drawings:

40 Figure 1 is an elevation looking at the inner side of my improved driving box, the box being shown in connection with a locomotive drive axle and frame of conventional type.

45 Figure 2 is a vertical sectional view on the line 2—2 of Figure 1, and looking in the direction of the arrows.

Figure 3 is a vertical sectional view on the line 3—3 of Figure 1 and looking in the 50 direction of the arrows.

Figure 4 is a horizontal section on the line 4—4 of Figure 1 and looking in the direction of the arrows,

55 Figure 5 is a detail elevation looking at the outer side of the box body, and

Figure 6 is a detail perspective view of the box, the parts being shown disassembled.

In order to facilitate an accurate understanding of the construction, operation and mounting of my improved driving box I 60 have, in the drawings, shown the invention in connection with a locomotive frame 10 of conventional type. The binder bar of the frame is indicated at 11 and coacting with the legs respectively of the frame is the usual 65 shoe 12 and wedge 13. A conventional drive axle is indicated at 14, this axle carrying at its adjacent end a drive wheel 15.

In carrying the invention into effect I employ a box body 16 adapted to snugly but 70 slidably fit between the shoe and wedge 12 and 13 respectively to coact therewith, the box body being provided with a medial journal receiving recess opening through the lower end thereof. Projecting laterally from 75 the outer side of the box body at the upper end portion of said recess is a flange or projection 17 conforming to the outline of the recess and having straight sides joined by an arcuate connecting portion. This arcuate 80 connecting portion of the flange is, as particularly shown in Figure 6, provided with a beveled face 18 sloping downwardly and outwardly toward the outer edge of the flange. Seated within the upper end portion 85 of the journal receiving recess of the box body is a crown brass 19 supported at its ends by transverse ribs 20. The crown brass bears over the adjacent journal of the axle 14 in the usual manner and, as will be observed, the flange 17 provides an extended bearing for the crown brass at the outer side 90 of the body, the flange being cut away to receive the brass and the ribs 20 extending across the end portions of the flange at their 95 lower terminals. At its inner side the box body is formed with lateral flanges 21 coacting one with the shoe 12 and the other with the wedge 13 at the inner side of the frame.

Depending from these flanges at their lower ends are lugs 22 and projecting from the lower ends of the side portions of the box body at their outer edges are outwardly directed lugs or flanges 23 which depend below said side portions and substantially 100 conform in thickness thereto. At their upper ends, the lugs 23 are provided with inwardly and downwardly sloping concave shoulders 105 tilted in the direction of the journal receiving recess of the body.

Removably fitted over the drive axle 12 at the outer side of the frame is a face plate 25. The side portions of this face plate are, at their inner edges, provided throughout the major portion of their length with flat vertical faces 26 adapted to snugly fit the straight end portions of the flange 17 of the box body, while between the upper ends of said faces, the plate is provided with an arcuate outwardly beveled edge 27 to snugly fit the beveled face 18 of said flange. At the lower ends of the faces 26, the inner edges of the side portions of the plate are cut away to provide inwardly and downwardly sloping convex shoulders 28 tilted to coact with the shoulders 24. Thus, as will be seen in view of the preceding description, the box body may be slid along the drive axle at the inner side of the frame and projected through the frame when the face plate 25 may then be inserted between the outer side of the frames and the wheel hub to be forced downwardly over the flange 17 and accordingly moved into active position embracing said flange. When thus in place, the face plate will, of course, seat flat against the outer face of the box body, the side portions of the plate coacting at their rear faces with the side portions of the box body, it being observed in this connection that the end portions of the flange 17 are of less thickness than the side portions of the box body. Downward movement of the face plate will, of course, be limited by the engagement of the beveled inner edge 27 of the face plate with the beveled edge 18 of the flange as well as by the engagement of the shoulders 28 of said plate with the shoulders 24 of the lugs 23.

Upstanding from the upper end of the plate at its outer side is an arcuate flange 29 and formed in the outer side face of said plate is, as particularly shown in Figure 4, an arcuate channel extending about the opening through the plate. This channel is substantially dovetailed in cross section and engaged in the channel is a hub bearing 30. As will be observed, this bearing overlies the major portion of the area of the outer side of the plate and is presented to the hub of the drive wheel to receive the wear thereof. As will be appreciated, the bearing may be renewed from time to time as may be found necessary. Formed through the flange 29 as well as through the upper side portion of the bearing is an opening 31.

Formed through the box body adjacent its upper corners are openings 32 which, at their outer ends, enter recesses 33 in the outer side of the box body. Freely fitted through said openings are bolts 34 provided, as particularly shown in Figure 6, with flat heads 35 adapted to be freely received within the recesses 33 lying flush with the outer

side of the box body and provided with convex inner end edges. Threaded upon the bolts are nuts 36 and it is now to be observed that the inner ends of these bolts are provided with openings 37 therethrough at substantially right angles to the heads 35. These openings are designed to receive cotter pins 38 for locking the nuts against displacement. Formed through the upper end of the face plate 25 adjacent opposite ends of the flange 29 are slots 39 which enter cylindrical recesses 40 in the inner side of the plate, these recesses opening through the bearing 30 and the bottom walls thereof being provided with concave seats at substantially right angles to the slots. The slots are adapted to freely receive the heads 35 of the bolts therethrough while the recesses 40 are of such diameter that the bolt heads may loosely turn therein. As will thus be appreciated, the bolts may, without removing the nuts therefrom, be retracted through the box body to dispose the heads of said bolts in the recesses 33. Consequently, the face plate may then, as previously described, be shifted downwardly between the box body and the hub of the drive wheel to active position. Then, the bolts may again be projected for shifting the bolt heads through the slots 39 of the face plate to dispose the heads of the bolts in the recesses 40. This done, the bolts may be given a half turn to engage the convex inner end edges of the heads thereof in the concave seats of the bottom walls of said recesses for locking the bolts against rotation when the bolt heads will coact with the face plate so that the nuts 36 may be tightened for securely binding the plate against the outer side of the box body.

Attention is now directed to the fact that when the face plate is, as just previously described, secured in place, the plate will be firmly held against upward movement so that the shoulders 28 of said plate will be maintained in binding engagement with the shoulders 24 of the lugs 23 of the box body. Consequently, these shoulders will lock the lower end portions of the plate tightly against the box body. The shoulders will thus coact with the bolts 34 for firmly securing the face plate flat against the outer side of the box body and will eliminate the necessity for the use of fastening devices similar to said bolts at the lower end of the face plate. Further, said shoulders will, as will be seen, coact to lock the end portions of the face plate against spreading. The face plate is, as will be particularly observed upon reference to Figure 4, of a width to overhang the box body at its outer side so that the face plate will thus provide flanges at the outer side of the box body coacting one with the shoe 12 and the other with the wedge 13 and cooperating with the

flanges 21 of the box body for securing the box upon the frame 10. In the drawings, I have shown a spring saddle 40 rested upon the upper end of the box. As will be observed, one leg of this saddle will engage the upper end of the face plate so that the weight sustained by the saddle will act to resist possible upward thrust against the face plate and will accordingly tend to eliminate possible undue strain upon the outer end portions of the bolts 34.

To remove the box, the nuts 36 of the bolts are first loosened and in this connection it is to be observed that since, as previously noted, the openings 39 through the inner end portions of the bolts lie at substantially right angles to the bolt heads 35, said openings will provide a means whereby the position of the bolt heads with respect to the vertical may be readily determined. Consequently, after the nuts 36 have been loosened, the bolts may be rotated to easily position the bolt heads in alignment with the slots 39 in the face plate, when the bolts may then be retracted for drawing the bolt heads through the face plate and into the recesses 33 in the box body. The face plate will then be freed so that a suitable tool may be engaged in the opening 31 through the flange 29 of said plate and the plate lifted upwardly and removed. This done, the box body may be readily shifted inwardly along the drive axle and also removed. I accordingly provide a construction whereby the box may, without removing the drive wheels, be readily displaced. Thus, with minimum difficulty, access may be readily had to the shoe and wedge and, as will be noted, the shoe and wedge may, without removing the frame brace, be also displaced. Accordingly, liners may be readily positioned beneath the shoe and wedge for lining the box.

In connection with my improved box I preferably employ a grease cellar 42. This cellar is mounted within the journal receiving recess of the box body to confront the lower side of the adjacent journal of the drive axle and, at its upper end, abuts the lower edges of the ribs 20. Removably supporting the cellar in place is a plate 43 detachably secured by bolts 44 engaged through the lugs 22 and 23 of the box body. As will be noted, the cellar is provided at its inner end with a sight window 45 in order that the level of the grease within the cellar may be readily ascertained. However, since this cellar is to be made the subject of a separate application it will not be further described herein.

Having thus described the invention, what is claimed as new is:

1. A journal box including a box body, a face plate seating against the outer side of the box body, and means securing the plate to the box body, said means being rotatable

to a position whereby such means may be retracted to free the plate for removal in a vertical plane parallel to the adjacent face of the box body.

2. A journal box including a box body, a face plate seating against the outer side thereof, and means carried by the box body and engaged with the plate for securing the plate to the box body, said means being rotatable to a position whereby such means may be retracted upon the box body to free the plate for removal in a plane parallel with the box body.

3. A journal box including a box body provided with recesses, a face plate seating against the outer side of the box body, the plate being provided with slots therethrough entering recesses in the outer side of the plate, and bolts engaging through the box body and said slots for securing the face plate to the box body, said bolts being provided with heads freely received in the recesses of the plate whereby the bolts may be rotated to dispose the heads thereof in alignment with said slots and then retracted through the face plate to dispose said heads in the recesses of the box body and thus permit removal of the face plate in a vertical plane parallel to the adjacent face of the box body.

4. A journal box including a box body provided at its outer side with a lateral flange having end portions joined by a curved connecting portion, the end portions being formed with straight outer faces and the connecting portion being formed with a beveled face, a face plate seating against the outer side of the box body to embrace said flange, the face plate being formed with side portions having parallel faces engaging the straight faces of the end portions of the flange and said plate being further provided between its parallel faces with an inclined face coacting with the beveled face of said flange, and means detachably securing the plate to the box body.

5. In a journal box, a box body, a face plate seating against the outer side thereof, coacting means carried by the plate and body respectively for locking one end portion of the plate to the body, and means carried by the body and engaged with the plate for securing the opposite end portion of the plate to the body, said last mentioned means being rotatable whereby such means may be retracted to free the plate and permit removal thereof in a vertical plane parallel to the adjacent face of the box body.

6. A journal box including a box body having outwardly projecting lugs providing longitudinally inclined shoulders having their length sloping laterally upward and forward away from the box body, a face plate seating against the outer side of the box body and having downwardly inclined

shoulders confronting said first mentioned shoulders, the plate being movable upwardly against the outer side of the box body, and means securing the plate against upward movement whereby the shoulders of the face plate will be held to coact with the shoulders of the box body for securing the plate against outward movement away from the box body.

10. 7. A journal box including a box body provided with longitudinally inclined shoulders having their length sloping laterally upward and forward away from the box body and tilted toward each other, a face plate seating against the outer side of the box body and having end portions provided with shoulders tilted to coact with said first mentioned shoulders for sustaining the end portions of the plate against spreading, the plate being removable upwardly against the outer side of the box body, and means locking the plate against upward movement.

8. A journal box including a box body having concave longitudinally inclined shoulders having their length sloping laterally upward and forward away from the box body, a face plate seating against the outer side of the box body and having end portions provided with convex shoulders mating with said first mentioned shoulders for sustaining the end portions of the plate against spreading, the plate being removable upwardly in a plane parallel to the adjacent face of the box body, and means locking the plate against upward movement.

9. A journal box including a box body having outwardly projecting lugs formed at their upper ends with concave shoulders inclining upwardly away from the box body, a face plate seating against the outer side of the box body and provided with end portions having downwardly inclined convex shoulders coacting with said first mentioned shoulders for locking the face plate to the box body and sustaining the end portions of said plate against spreading, the plate being removable upwardly in a plane parallel to the adjacent face of the box body, and means locking the plate against upward movement.

10. A journal box including a box body, a face plate seating against the outer side thereof and removable upwardly in a plane

parallel to the adjacent face of the box body, and bolts extending from the box body through the plate locking the plate against upward movement and provided with flat heads coacting with the plate, the bolts being rotatable to a position whereby the heads thereof may be retracted through the plate for releasing the plate.

11. In a journal box, the combination with a box body, and a face plate seating against the outer side of the box body and removable upwardly in a plane parallel to the adjacent face of the body, of coacting means fixed upon the face plate and box body respectively and inclined lengthwise laterally and forwardly with respect to the outer side of the box body for securing the face plate against outward movement away from the box body, and means securing the plate against upward displacement.

12. A journal box including a box body provided with longitudinally inclined shoulders, having their length sloping laterally upward and forward with respect to the box body, a face plate seating against the outer side of the box body and removable upwardly in a plane parallel to the adjacent face of the box body, the face plate being provided with downwardly inclined shoulders confronting said first-mentioned shoulders, and means securing the face plate against upward movement whereby the shoulders of the face plate will be held to coact with the shoulders of the box body for securing the face plate against outward movement away from the box body.

13. In a journal box, the combination of a box body provided adjacent its inner side with pedestal flanges and having a forwardly extending projection at its outer side, said projection being provided with straight vertically disposed side faces, a face plate seating against the outer side of the box body overhanging the body to provide pedestal flanges to cooperate with said first mentioned flanges and straddling said projection to coact with the straight faces thereof, said faces locking the face plate against rotative movement, and means connecting the face plate with the box body.

In testimony whereof I affix my signature.

ARTHUR T. KUEHNER. [L.S.]
